F. ENSSL

FRUIT JUICE EXTRACTOR

Filed Aug. 10, 1925

UNITED STATES PATENT OFFICE.

FRED ENSSLER, OF ROSELLE, NEW JERSEY.

FRUIT-JUICE EXTRACTOR.

Application filed August 10, 1925. Serial No. 49,329.

This invention relates to improvements in fruit juice extractors, more particularly to devices for extracting the juice from oranges, lemons, grape fruit, and the like, and has 5 for one of its objects to provide a simply constructed apparatus whereby an extractor element may be caused to rotate when pressure is applied thereto, or to the section of fruit disposed thereon, to thoroughly extract 10 the juices therefrom and permit them to fall into a suitable receptacle.

Another object of the invention is to provide a device of this character having means whereby the extracted juices are thrown by 15 centrifugal force away from the extractor element and thereby prevented from lodging thereon.

Another object of the invention is to provide a device of this character wherein the 20 several parts are separable for cleansing or for the renewal of broken or impaired parts without discarding the unbroken or unimpaired portions.

In the drawings illustrative of the preferred embodiment of the invention.

Fig. 1 is a longitudinal sectional elevation of the improved device.

Fig. 2 is a top plan view.

The improved device includes a body preferably cylindrical and formed with vertical 30 sides 10 and with the bottom 11 sloping and disposed intermediate the sides, thereby forming a chamber or space 12 beneath the sloping bottom.

The lower edge of the body is preferably supplied with supporting feet 13 and its upper edge inturned in the form of an overhanging flange 14 surrounding the upper open end of said body.

The space within the body above the floor 40 constitutes the receptacle in which the extracted juices are first received, and which escape through a lateral opening 15 and over a sloping spout 16 at the lower end of the bottom 11.

Formed upon the sloping bottom 11 is a perforated hub or boss 17, the perforation being internally threaded with a double or quick action thread, the hub operating as a 50 guard to prevent the extracted juices from running through the threaded opening into the chamber 12, as will be obvious.

Operating through the threaded opening in the hub 17 is a member 18 having double 55 or quick action threads to correspond and

engage the threads of the hub. By this arrangement, it will be obvious that when the member 18 is moved longitudinally of its axis, it will be rotated.

Attached to the upper end of the member 60 18 is an extractor element including a conical portion 19 having a plurality of curved relatively sharp ribs 20 and encompassed adjacent its bottom by an upwardly curved flange or trough 21 provided with a plurality of lateral perforations 22 for the escape of the extracted juices.

Depending from the bottom of the floor 11 are guide rods 23 and slideable on the guide rods is a cross head member 24, the 70 latter being yieldably supported on the rods, by springs 25.

At its lower end the threaded member 18 is reduced as shown at 26 and rotatively stepped by the reduced portion in a socket in 75 the cross head 24, the socket having a ball race 27 to receive anti friction balls 28.

At its lower end the reduced portion 26 of the member 18 is formed with an encircling channel 29 to receive a spring key member 30, 80 to enable the member 18 to be detachably and rotatively locked to the cross head.

The springs 25 are supported by adjusting nuts 31, to enable the tension of the 85 springs to be controlled.

By this simple arrangement, when a section of fruit, for instance the half of a lemon, orange, grape fruit or the like is placed upon the extractor and forced downwardly and held from turning by the hand, the quick 90 action threads of the member 18 coacting with the quick action threads of the hub 17 will cause the member 18 and the extractor carried thereby to be rotated as they move downwardly and thus effectually extract the 95 juices and cause them to flow into the trough 21 from which they will escape through the orifices 22 and be also thrown by the centrifugal force generated by the rotating extractor and its trough against the side walls 100 of the receptacle chamber and flow thence through the opening 15 and spout 16 into a suitable vessel, not shown, the flange 14 preventing the juices from being thrown upwardly.

In the meantime the downward movement of the member 18 will depress the cross head 24 against the resistance of the springs 25, and when the downward pressure is removed the reaction of the springs will return the 105 110

member 18 and extractor to its former position when the extracted fruit section can be detached.

The body 10 will be formed of glass, glazed porcelain, aluminum or other noncorrosive material, while the extractor element will likewise be formed of glass, porcelain, aluminum or other noncorrosive material or compounds. The metal parts will also be of noncorrosive compounds or plated, or otherwise protected from the action of the fruit juices.

As before stated all the parts are separable for cleansing and readily disconnected and assembled.

Claims:

1. In a device of the class described, a receptacle having a bottom provided with a threaded opening surrounded by a guard flange upstanding from said bottom and also having a lateral discharge extending from said bottom, a threaded member operative through the threaded opening, and an extractor element attached to the threaded member.

2. A fruit juice extractor including an extractor element having a ribbed cone, and means for rotating said extractor element when pressure is applied to said cone by means of a piece of fruit in the hand of the operator.

3. A device of the class described, including a body, an extractor element in said body, and means for causing said extractor element to be rotated by the pressure applied to the fruit by the hand of the operator.

4. A device of the class described, including a support having a threaded opening therein, a threaded member operating through said opening, and a cone-shaped extractor head against which fruit is adapted to be pressed, said extractor secured to said threaded member and being rotated thereby when pressure is applied axially to said extractor head.

5. A device of the class described, including a body having a bottom provided with a threaded opening, a threaded member operating through said opening, a cone-shaped extractor head carried by said threaded member and rotatable therewith, guide rods carried by said bottom, and a cross-head element slidable on said guide, said extractor head and threaded member being rotated by the pressure applied to the fruit by the hand of the operator.

6. A device of the class described including a screw member, and a cone-shaped extractor head carried on said member and rotatable therewith, said extractor head and screw member being rotated by the pressure applied to the fruit by the hand of the operator.

65 7. A device of the class described, includ-

ing a screw member, a cone-shaped extractor carried thereby, means causing rotation of said screw member and extractor when pressure is applied to the latter by means of a piece of fruit engaged therewith, and a spring supported carrier for said screw member offering resistance to said pressure.

8. A device of the class described, including a body having a bottom and an open upper end, an extractor element within said body and normally supported adjacent said open end, and means supporting said element and having a bearing in said bottom for causing said element to rotate when pressure is applied thereto by means of a piece of fruit in the hand of the operator.

9. A device of the class described, including a body having a bottom and an open upper end, an extractor element within said body and normally supported adjacent said open end and adapted for rotary and vertical movements relative to said body, and a screw member having threaded engagement with said bottom and supporting said extractor element and operable to rotate the same when said element is moved downwardly by pressure thereon.

10. A device of the class described, including a body having a bottom and an open upper end, an extractor element within said body and normally supported adjacent said open end and adapted for rotary and vertical movements relative to said body, a screw member having threaded engagement with said bottom and supporting said extractor element and operable to rotate the same when said element is moved downwardly by pressure thereon, and means for restoring said element to its normal position when said pressure is relieved.

11. A device of the class described, including a body having a bottom and an open upper end, an extractor element within said body and normally supported adjacent said open end and adapted for rotary and vertical movements relative to said body, a screw member having threaded engagement with said bottom and supporting said extractor element and operable to rotate the same when said element is moved downwardly by pressure thereon, guide rods depending from said bottom, a cross-piece connected to said screw member and movable along said rods, and springs engaging said cross-piece for exerting an upward pressure on said cross-piece to restore said extractor element to normal position when pressure on said extractor element is relieved.

12. A device of the class described, including a body having a bottom, a screw member rotatably mounted in said bottom and movable vertically in the body, and an extractor element carried by the upper end of said screw member and having both vertical and rotary movements therewith.

13. A device of the class described, including a body having a bottom, a screw member rotatably mounted in said bottom and movable vertically in the body, an extractor element carried by the upper end of said screw member and having both vertical and rotary movements therewith, and means yieldably supporting said screw member and extractor in a raised position within
10 said body.

14. A device of the class described, including an inclined support, a screw member extending transversely through the support and having both rotary and transverse movements relative thereto, and an extractor 15 carried by one end of said screw member and movable therewith both rotatably and toward and away from said support.

In testimony whereof I affix my signature.
FRED ENSSLE.
